CLAIM

The ornamental design for a POS terminal, as shown and described.

DESCRIPTION

FIG. 1 is a perspective view of a POS terminal, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and

FIG. 8 is a perspective view of the POS terminal in a configuration of use showing an external cover.

In the drawings, the broken lines depict environmental subject matter only and form no part of the claimed design.

1 Claim, 8 Drawing Sheets
